METHOD FOR MAKING ROADS

Original Filed April 3, 1930

FIG. 1.

UNITED STATES PATENT OFFICE

2,063,400

METHOD FOR MAKING ROADS

John F. Robb, Cleveland Heights, Ohio, assignor
to Koehring Company, Milwaukee, Wis., a cor-
poration

Original application April 3, 1930, Serial No.
441,279. Divided and this application Novem-
ber 24, 1934, Serial No. 754,619

1 Claim. (Cl. 94—46)

This is a division of my copending applica-
tion for Letters Patent, Serial No. 441,279, filed
Apr. 3, 1930.

This invention has to do with machines for
building concrete roads, known as paving ma-
chines, and a method of supplying and deliver-
ing concrete aggregates, or road paving ma-
terials, to a road subgrade upon which they are
to be laid. The method and apparatus com-
prising this invention is especially useful in
conjunction with central mixing plants and de-
livery trucks used to transport concrete aggre-
gates from such plants to the site upon which
the aggregates are to be laid. The delivery
truck utilized for the purposes of the invention
may be of the type equipped with a mixer, in
which event the mixing of the aggregates may
be performed independently of the central mix-
ing plant.

In carrying out my invention there is pro-
vided apparatus in the form of a portable ma-
chine adapted to travel over the road subgrade
upon which the concrete or road paving ma-
terials are to be laid. This machine comprises
self-propelling instrumentalities; for instance, a
motor or engine arranged to drive the traction
wheels of the machine. Additionally are pro-
vided a receiving hopper for the aggregates and
spreading means for moving the materials de-
livered to the hopper, to all portions of the
hopper, a spreading unit being thus provided.
It is contemplated by the construction of the
apparatus that the delivery truck which is to
supply the road paving materials to the spread-
ing unit, and which may comprise a mixer,
shall be coordinated in its movement relatively
to the apparatus. In other words, as the spread-
ing apparatus moves along the road subgrade
and lays the paving materials thereon, the de-
livery truck which supplies the aggregates to
the spreading apparatus will likewise move in
coordination therewith, its movement conform-
ing with the movement of the paving or spread-
ing apparatus, and the depositing of the road
paving materials on the subgrade will be con-
tinuous with the supplying of such materials to
the spreading hopper from the delivery truck
or mixer.

More specifically describing a road paving
operation with my apparatus, it is noted that
the portable machine or apparatus will advance
along the subgrade longitudinally thereof and
will continuously feed the aggregates to the
subgrade from the spreading hopper of the ap-
paratus. An operator will be seated on the ma-

chine to maintain it in motion at a suitably
determined rate of speed. In advance of the
apparatus or portable machine aforesaid, and
also traveling on the subgrade, will be the de-
livery truck or truck mixer which forms a con-
taining member and supplies the aggregates to
a chute disposed longitudinally of the apparatus
centrally thereof. In this chute is a conveyor
of a suitable type, as for instance a screw
conveyor, which carries the materials delivered
from the supply truck or truck mixer to the
spreading hopper in which are located suitable
spreading devices. By coordinating the speeds
of the apparatus of the portable machine of
my apparatus and the supply truck or truck
mixer, it is evident that a speedy depositing of
the road aggregates upon the subgrade may be
effected.

In the drawing—

Figure 1 is a top plan view of apparatus con-
structed in accordance with my invention and
adapted to practice the method thereof as here-
inbefore set forth.

Figure 2 is a perspective view of the discharge
means located at the lower portion of the distrib-
uting hopper.

Describing my apparatus specifically, it is no-
table that the hopper E' is carried by the port-
able frame A' equipped with the traction wheels
1 adapted to travel along the road forms 2, or
any other supporting means, as the apparatus
moves lengthwise of the road subgrade upon
which the paving aggregates are to be laid. The
hopper E' is provided with a shaft I' extending
substantially the entire length of the hopper. 30
Mounted on the shaft I' are oppositely directed
spiral levelling blades H' and H'' of substan-
tially equal length, these levelling blades being
disposed at the opposite sides of the longitudi-
nal axis of the frame A' and being adapted to 35
act upon paving materials delivered to the hop-
per E' so as to carry forward materials from
a central point where they are received in the
hopper, toward the opposite ends of the hopper
in a manner to level off the materials so that 40
they may feed to the subgrade through the dis-
charge means 56 and 57 at the lower end of
the hopper. At one side thereof the hopper E'
is provided with an upwardly sloping chute G'
which is immovable with respect to said hopper. 50
A shaft 29 is mounted in bearings 30 and 31
in the hopper E' and chute G', respectively. Se-
curely fixed on the shaft 29 is a charging spiral
blade 32 which ends at a point within the hop-
per E' just short of the shaft I'. The shaft 29 55

is provided with a worm gear drive between it and the shaft 1', said worm gear drive including a worm and worm gear or wheel enclosed in an oil-tight casing 31. Any suitable gearing may 5 be employed in lieu of the said worm and worm gear drive whereby to transmit motion to the conveyor 32 from the shaft 1'. The delivery truck L, which may be provided with a mixer, is adapted to deposit aggregates on the chute 10 G', whereupon said aggregates are transferred by means of the blade or conveyor 32 to the inner adjacent ends of the levelling blades H' and H''. The said blades distribute the aggregates evenly from the center of the hopper E' 15 toward the extremities thereof.

Mounted on the support A' adjacent to the side of the hopper E' opposite from the chute G' is an engine F' which furnishes the motive power for operating the hopper instrumentalities and certain other mechanism now to be set 20 forth.

For purposes of propulsion a shaft 34 on the engine F' has a worm and wheel drive gearing, said gearing being disposed in an oil-tight casing 36. The ends of the shaft 35 are disposed in bearings 37 on the framework of the support A', and bevel gears 38 are mounted on the projecting ends of said shaft. The rear axle 39 is provided with a differential gearing enclosed 30 in a housing 40 and a drive shaft 41 therefor has a gear 42 meshing with a gear 43 mounted on the clutch shaft 44. Said shafts may be supported on the framework in any suitable manner. The clutch shaft 44 is provided with 35 a clutch 45 having driving gears 46 selectively engageable with one of the gears 38 whereby to propel the portable support A' in one direction or another or to maintain the same at rest. For the purpose of moving the clutch 45 to its various positions, operating instrumentalities 41 are provided, including a hand control lever 48 within easy reach of the operator who will be seated on the seat 49.

The other gear 38 mounted on the shaft 35 45 meshes with the gear 50 mounted on a clutch shaft 51. A clutch 52 coacts with a gear 53 mounted on the shaft 29. The clutch 52 also is provided with operating instrumentalities 54 including the operating lever 55 operable by the 50 attendant.

For the purpose of providing for the deposit of the aggregates that have been levelled off in the distributing hopper E', onto the subgrade below, I provide two doors 56 and 57, see Figure 2. An operating shaft 58 is suitably supported on the framework of the support A' and has fastened thereto a control lever 59. A crank arm 60 is mounted for rotation with the shaft 58 and has pivotal connection with the rod 61 which is in turn pivoted to an extension or arm on the pivoted door 56. It is thus seen that operation of the lever 59 will cause the shaft 58 to actuate the door 56 to regulate the thickness of the layer of concrete or paving material to be deposited, and also to close half of the bottom opening of the hopper E', if so desired. Loose on the shaft 58 is an operating lever 63 pivotally connected to the door 57, similarly to the connections of the lever 59 with the door 56. Movement of the lever 63 with respect to the shaft 58 in an arcuate path will result in the operation of the door 57 in accordance with the requirements of the job.

The rear axle 39 and a front axle 64 are provided with instrumentalities 65 which make possible the adjustment of the length of the axles to correspond with the width of the road to be paved.

With the construction of my apparatus as above set forth, it is apparent that I eliminate the necessity of raising and lowering mechanism for handling the aggregates in transferring the same from the supply truck or mixer to the 10 hopper E'.

In the operation of my invention the apparatus comprising the spreading hopper E' and associated spreading instrumentalities will preferably move along the road subgrade at a speed 15 determined by the operator at the seat 49. At the end of the apparatus where the chute G' is located, a supply truck or mixer truck will supply the road paving materials or aggregates to the chute G' whilst the paver or spreading apparatus is in motion and while the said supply truck or mixer is similarly in motion. A decided advantage of this construction is that the delivery truck supplying the aggregates to the chute G' may propel itself along the subgrade 20 in front of the support A' in conformity with the movement of the paver as controlled by the operator seated at 49, so that the deposit of the aggregates on the subgrade may be continuous with the supply of aggregates to the 25 hopper E'. A plurality of the delivery trucks or mixers will of course be available to cooperate with the apparatus so that there will be no loss of time in between delivery of fresh batches of materials to the chute G'. 35

My new method of laying paving aggregates upon road subgrades involves especially the movement or operation of the spreading or paving apparatus simultaneously with the movement of the supply truck or containing member which 40 operates in conjunction with the operating apparatus, thus affording a practically continuous supplying of the concrete or mixing aggregates to the spreading mechanism so that continuous progressive operation of laying down the aggregates is ensured. When the aggregates are delivered by the mixing or supply truck to the chute G' they will be acted upon promptly by the conveyor or spiral blade 32 so as to be carried to the hopper E' for deposit therein and 45 feeding therefrom. 50

Having thus described my invention, what I claim as new and desire to secure by Letters Patent of the United States, is—

The method of laying road aggregates which comprises advancing over the subgrade a power driven hopper unit adapted to receive and distribute the aggregates, successively bringing separate power driven aggregate-containing units into position so that the aggregates contained therein may be deposited in the hopper unit, advancing the respective aggregate containing units along the subgrade at a speed corresponding to the speed of movement of the hopper unit and depositing the aggregates into the hopper unit during the advancing movement of the hopper unit, whereby the supply of aggregates to the hopper unit will be substantially continuous, and spreading the aggregates in the hopper unit in a direction at right angles to the direction of travel thereof as the hopper unit and containing units progress along the subgrade. 65 70

JOHN F. ROBB.
